[57] CLAIM

The ornamental design for a bottle, as shown and described.

DESCRIPTION

FIG. 1 is a top, front perspective view of a bottle showing our new design;

FIG. 2 is a bottom, rear perspective view thereof;

FIG. 3 is a front elevation thereof;

FIG. 4 is a top plan view thereof;

FIG. 5 is a right side elevation thereof, the left side elevation is the same except for the conventional screw threading on the bottle neck;

FIG. 6 is a bottom plan view thereof.

*FIG. 1**FIG. 2**FIG. 3*

*FIG. 4**FIG. 5**FIG. 6*
